TELEGRAPH PRINTING SYSTEM

James A. Spencer, Teaneck, N. J., assignor to
 Radio Corporation of America, a corporation of
 Delaware

Application May 16, 1939, Serial No. 273,846

19 Claims. (Cl. 178—17.5)

This invention relates to mechanism for use in radio and wire telegraph systems. In multiplex telegraphy using equal length code characters a plurality of channels, each having its own tape transmitter at the sending station and printing mechanism at the receiving station, are successively assigned to a radio or wire link for the duration of one code group. This enables one to utilize all the time allotted to each channel for the sending of the messages, while the local printing functions, such as setting up the tape combinations and operating the printer, are taken care of for one channel while another channel is sending on its allotted time. In prior art, simplex telegraphy for equal length code characters, however, the whole time is not utilized in transmission of the character code signals. Therefore the connecting radio or wire link is kept idle while the local functions are being performed. In my copending application filed January 21, 1939, Serial No. 252,179, I disclosed a sending and receiving mechanism that remedies this difficulty but a large number of electromagnets and associated contacts are provided for storing the signals while local functions are being performed.

It is an object of this invention to provide a simple system with a minimum number of electromagnets for utilizing all the circuit time for transmission of signals having equal length code characters and to perform the local operations while another combination is being transmitted.

Another object is to provide a simplified system with a minimum number of electromagnets in single channel telegraphy, employing equal length code characters in which all the circuit time is used for transmission of the message.

Another object is to provide a simple single channel system using equal length code characters by storing a part of a code unit in a sending or receiving device for sufficient time to permit the performing of its local operations.

Other objects will appear in the following description, reference being had to the drawings in which:

Fig. 1 is a circuit diagram of the apparatus at the sending station.

Fig. 2 is a section of a perforated tape giving the perforations for the letters of the alphabet in a seven unit equal length code.

Fig. 3 is a graph of the potential or current of a signal message.

Fig. 4 is a circuit diagram of the receiving system.

Fig. 5 is an illustration of the battery connec-

tions for operation of the sending and receiving mechanism.

Fig. 6 is a diagrammatic illustration of a portion of a telegraph printer.

Fig. 7 is an illustration of part of the printing mechanism.

Referring to Fig. 1, T indicates generally the tape transmitter such as the Benjamin, or other type, which in this case has seven seeker pins resiliently urged by operating magnet 2' against a perforated tape which holds the seeker pin from further movement if no hole has been punched therein but if a hole is present for any particular seeker it engages its contact. There are seven of these contacts numbered 1 to 7 in the drawings. The perforated tape and the mechanism for moving the tape forward and raising the seeker pins thereagainst have not been illustrated because they are old and well known in the art.

The contacts 1 to 7 inclusive, are connected respectively to selector magnets S1, S2, S3, S4, S5, S6 and S7. Selector magnets S1 to S3 inclusive, operate armatures 8, 9 and 10, which immediately upon being actuated release levers 11, 12 and 13. These levers break contacts 14, 15 and 16 connected to the negative terminal and close contacts 17, 18 and 19, connected to the positive terminal. Switch tongues 20, 21 and 22 making and breaking these contacts are connected respectively to segments s1 to s3 of the distributor generally indicated at 23. This distributor is run at a speed that is maintained constant by well known mechanism which is not illustrated, but reference is made to patents to Callahan, Mathes, and Kahn, No. 2,010,505, and the patent to Mathes, No. 2,038,375, for a detailed description of such devices. Brushes and short-circuiting bar 24 connect these segments successively to collector ring 25 and to outgoing line 27 of the radio or wire link as the case may be.

Armatures 28, 29, 30 and 31 which act as catches or supports for levers 32, 33, 34 and 35, cannot be moved by selector magnets S4, S5, S6 and S7, respectively, except when they are unlocked by their respective levers. These levers are diagrammatically illustrated as being all connected together for operation by armature 36 when magnet 37 is energized. This magnet 37 is electrically connected to switch tongue 38 normally held out of engagement with positive contact 39 by levers 41 when held in position by armature 42. This armature is operated by magnet 43 which is connected to segment s'1 of the distributor 23. The segments s'1 to s'7 are part

of the distributor 23 and are successively connected by brush 44 to collector ring 45 which is connected to the positive terminal 46.

Reset magnet 47 is connected to switch tongue 48 of relay 49. This relay has operating coil 50 connected between ground and segment s'6. This magnet has a spring controlled armature 51 which holds lever 52 in position to prevent tongue 48 from engaging contact 53. Reset magnet 47 operates bell crank 54 and through its arm 55 moves lever 11 back to reset condition with switch tongue 20 in engagement with contact 14. When the magnet is deenergized and the lever has been reset spring 56 moves the armature back under the lever 11 to hold it in position. Levers 12, 13 and 52 are similarly resiliently actuated and are reset by arms 57, 58 and 59 which are connected to bell crank 54 by shaft 60 so that they rotate in unison with arm 55. Reset magnet 37 moves the arms 32, 33, 34, 35 and 61 and unlocks the armatures or catches 28, 29, 30 and 31 engaging the levers 62, 63, 64 and 65. These levers in locked positions close the upper contacts and in the unlocked position open them and close the lower contacts. The arms 32 to 35 and 61, also reset the lever arms 62 to 65 and 41, and permit the springs to pull the armatures back into engagement with the respective lever arms when the magnets are deenergized.

In Fig. 4 the receiving apparatus is shown and it is identical with the apparatus of Fig. 1 with certain exceptions that will be referred to later. In view of the similarity of the construction and operation the reference characters in Fig. 4 have in general been given the same reference character as similar parts in Fig. 1 with the distinguishing letter *r* added thereto. In view of this a complete description of Fig. 2 is unnecessary since the description of Fig. 1 will enable one to understand Fig. 2.

The differences between Fig. 4 and Fig. 1 previously referred to are chiefly as follows:

The segments s'r1 to s'r7 of the distributor 23r, which is run synchronously with distributor 23, are connected to selector magnets S'r1 to S'r7 respectively. The printing magnet 73 is connected to switch tongue 39r in parallel with reset magnet 37r. Magnet 43r is connected to distributor s'r7 and the selector magnet 50r is connected to the third local segment s'r3.

The operation of the transmitter will now be described with the assumption that the word "hand" is being transmitted as a word in the message. It will be assumed that brushes 24 and 44 have just made engagement with segments s'4 and s'4 respectively, as all code combinations start at this time. This energizes tape transmitter magnet 2' and moves the tape so that the perforations for the letter H are in position over the seeker pins (see Fig. 2). Contacts 2, 5 and 6 are then engaged by their seeker pins while the other contacts are held from engagement with their seeker pins due to the absence of perforations. Magnets S₂, S₅ and S₆ are immediately energized. The armature of magnet S₂ moves and switch lever 12 drops, closing mark contact 18 and opening space contact 15. The armatures of magnets S₄ and S₅ cannot move at this time, as they are locked in the notches of their switch levers. Disregarding the previous signal that is being completed and referring only to the code signals for the letter H, it may be said that nothing happens when the brushes engage segments s'5, s'5, as the armature of selector magnet S₅ is

locked in position but the magnet remains energized.

When segment s'6 is engaged no current flows thereto but at this time the engagement of brush 44 with segment s'6 energized magnet 50. This at once energizes reset magnet 47 and at about the same time brush 44 leaves segment s'6 and deenergizes magnet 50. Reset magnet 47 moved the levers 55, 57 and 58 back into raised position and all catches except 9, were moved by their springs into position to support the levers if they had been lowered on receipt of the previous signal. Catch 9 was not moved because magnet S₂ is energized.

When segments s'7 and s'7 are engaged nothing happens as far as the letter H is concerned. When segment s'1 is engaged a negative pulse 74 (Fig. 3) is sent from the negative line through upper contact 14 segment s'1 to ring 25 and to the radio or wire link 27. This is the beginning of the transmission of the letter H. Prior to this time, namely, while the brush was moving over segments 4, 5, 6 and 7, the code signal was stored. Also at this time magnet 43 is momentarily energized and catch 42 moved from under lever 41 and tongue 38 engages contact 39. This energizes reset magnet 37, which raises levers 62, 63, 64, 65 and 41. This permits energized magnets S₅ and S₆ to attract their armatures. At about this time brush 44 leaves segment s'1 and relay 43 and magnet 37 are de-energized. The de-energization of magnet 37 drops levers 34 to 35 inclusive and 61, which leaves levers 62 and 65 in space position (negative current), as magnets S₄ and S₇ are not energized. Levers 63 and 64, however, drop to mark position (positive current) as armatures 29 and 30 are held out of the notches in such levers by the energization of magnets S₅ and S₆.

When the brushes engage segment s'2 a positive pulse 75 (Fig. 3) is sent over the line 27 as selector magnet S₂ is still energized and tongue 21 is in engagement with positive contact 18. Engagement of brush 44 with segment s'2 does not produce any result as it is a blank segment. Upon brush 24 engagement segment s'3 negative pulse 76 is sent over line 27 since selector magnet S₃ is not energized and the negative contact is in engagement with tongue 22. Segment s'3 is a blank and no current is passed when brush 44 engages it.

Engagement of brush 24 with segment s'4 sends out negative pulse 77 as selector magnet S₄ is not energized. Simultaneously brush 44 engages segment s'4 and tape transmitter magnet 2' is operated which retracts the seeker pins, moves the tape to position for the next letter A and raises the seeker pins, but only pins 1, 3 and 4 engage their contacts. (See Fig. 2.) This energizes selector magnets S₁, S₃ and S₄, and deenergizes selector magnets S₂, S₅ and S₆, for the previous letter H. The signal pulse for selector magnet S₂ has already been transmitted so deenergization of magnet S₂ cannot affect the transmission of the letter H. Also, the transmission of the letter H will not be affected by deenergization of selector magnets S₅ and S₆ because the levers 63 and 64 are in lowered position with the catches outside the locking notch.

When brush 24 engages segment s'5 positive pulse 78 is sent to line 27 as the tongue of selector s'1 is in engagement with the positive contact. Nothing happens when brush 44 engages segment s'5 except that tape operating magnet 2' would be energized if such magnet did not complete its

operation by engagement of the brush with segment $s'4$. This double connection is not absolutely necessary but since segment $s'5$ is otherwise a vacant one it is joined to $s'4$ to assure that the magnet will always operate. Upon brush 24 engaging segment $s'6$ positive pulse 79 is sent over the link 27 because selector lever 64 is in lowered position with catch 30 locked against movement by its spring. Also at this time reset magnet 47 is operated by engagement of brush 44 with segment $s'6$ which energizes relay coil 50. This stores the first and third code unit of the letter A by keeping selector magnets 61 and 63 energized with levers 20 and 22 reset for the next code combinations of the message. As the brush 24 reaches S7 negative pulse 80 is transmitted over line 27 because S7 was not energized for the code combination in the letter H. The letter H has now been fully transmitted and the combination for the next letter A has been set up.

When brush 24 engages segment $s'1$ positive pulse 81 of the combination for the letter A is transmitted and magnet 43 is energized by brush 44 engaging segment $s'1$. This moves armature 42 and permits arm 41 to drop and close contacts 38, 39, which energizes magnet 37 and causes levers 62 to 65 and 41 to be raised. Lever 28 will not be held by its catch and it is moved by magnet S4 which is energized. This permits lever 62 to drop to positive current position when magnet 37 is de-energized and the armature lever 28 is locked in attracted position, but levers 63, 64 and 65 are held in negative current position by the armatures of de-energized magnets S5, S6 and S7. As the brushes continue to rotate the transmission of the letter A will be completed by negative pulse 82, positive pulses 83 and 84 and negative pulses 85 and 86. A new combination is set up on the tape transmitter when segment $s'4$ is reached.

The letter N will be similarly transmitted by negative pulse 87, positive pulses 88 and 89 and negative pulse 90, positive pulse 91 and negative pulses 92 and 93. When segment $s'5$ was reached the combination for the letter D was set up and on the next rotation of the brushes positive pulse 94, negative pulses 95, 96, positive pulses 97, 98, and negative pulses 99 and 100 will be transmitted.

It will be seen that the transmission of the message is delayed one revolution of the brushes by storing the code units.

This momentary delay is of course not noticeable insofar as the speed of transmission of the message is concerned, but it gives ample time to perform the local function of setting up the tape transmitter for a code combination.

It will be apparent that one or more code units can be successively repeated without in any way changing the method of operation above described.

I have shown a circuit arrangement in Fig. 8 for converting positive and negative pulses at the receiver into on and off signals through polar relay 101 connected to incoming line 102. Obviously this would be omitted if this conversion were accomplished at some other point in the radio or wire link. The operation of the receiving apparatus is quite similar to that of the transmitting apparatus except the printer itself. The method of operation is as follows:

Referring to Figs. 4 and 6 and assuming that the first negative pulse 74 of the transmitted letter H, or other pulse formed therefrom, has arrived at the polarized relay 101, the switch tongue 75

of the relay will be moved against dead contact 103 and no current will flow when brush 24r engages segment $s'1$ of distributor 23r. Also, no current will flow from segment $s'1$ at this time.

When positive pulse 75 arrives at relay 101 the relay tongue will be moved against the positive contact 104. At this time brushes 24r and 44r will be on segments $s'2$ and $s'2$ and relay Sr2 will be energized. The energization of this relay closes the circuit to selector magnet 67 of the printer through contact 18r (see also Fig. 6). In the printer shown in Fig. 6 the latch and selector mechanism for relay 66 is the only one completely illustrated but the other relays have exactly similar parts.

When magnet 67 was energized it attracted one end of its armature 105 (note illustration for magnet 66) pivoted in the center, against the tension of its returning spring and projected the opposite end into notch 106 of selector bar 107, there being a selector bar for each selector relay. The armature is held in this position by latch 108 so that when the brush 24r leaves segment $s'2$ of the commutator the armature will remain in its operated position. The selector magnets 66 to 72 and their armatures 105 and latches 108 are all secured to the movable carriage 109.

When negative pulse 76 arrives the switch tongue of polarized relay 101 will be thrown against the dead contact 103 and printer magnet 68 will not be energized. At this time segment $s'3$ causes the operation of reset magnet 47r, resetting levers 11r, 12r, 13r and 52r, so they will be ready for the next code character. Negative pulse 77 like all negative pulses will not cause a selector magnet to be operated.

When positive pulse 78 arrives relay 101 will energize magnet 70 as brush 44r is in engagement with segment $s'5$. When brush 24r engages segment $s'6$ pulse 79 causes magnet 71 to be energized. As in the case of magnet 67, magnets 70 and 71 operated their armatures and projected their ends into notches (indicated only for magnet 66) in selector bars 110 and 111 fragmentarily shown in Fig. 6. All selector bars are broken away but each bar has a properly positioned notch such as notch 122 more particularly referred to later herein.

When magnets 67, 70 and 71 operated their armatures each of them also closed contacts through a cut-out shaft and lever, diagrammatically illustrated as simple switch contacts 113 arranged in parallel, each in Fig. 6, closing a circuit to relay 73 but as shown in Fig. 4, the circuit is open at contact 39r of relay 43r, connected to segment $s'7$ on commutator 44r. Therefore, when brush 44 engages this segment relay 43r is energized which closes contacts 39r and energizes magnet 37r causing it to reset levers 62r to 65r and also lever 41r, clearing the selector relays $s'4$ to $s'7$ for the next signal unit. Relay 43r also energizes relay magnet 73 which closes switch contacts 114 and energizes operating magnet 115. Armature 116 then moves the printed carriage 117 (the middle portion being shown broken away) towards the left by means of plunger 118.

Since the seven selector magnets 66 to 72 and their respective armatures are mounted on carriage 117 the selector bars 107, 110 and 111 are moved with the carriage because the projecting ends of armatures 105 of selector magnets 61, 70 and 71 engage the edges of notches identical

with 106. The remaining selector bars are not moved with the carriage. Shortly before the motion to the left is completed trip 119 engages latch 108 and permits the armatures similar to 105 to spring back into place. The armatures are freed from friction against the ends of notch 106 at this time by leaf spring 120 entering notch 121 in the three selector bars which snaps the selector bars slightly to the left. Selector magnets 67, 70 and 71 then resume their normal condition. When the three selector bars reach their extreme left-hand position notches 122 in the three selector bars corresponding to the letter H are in alignment, there being also notches in the other bars in alignment with notch 122 at this point. Pull bar 123 shown more in detail in Fig. 7, is then in position to drop into these aligned notches but it is held from this movement by the printing bail 124 engaging hump 125 on the pull bar.

When the carriage reaches its extreme movement to the left it opens switch contacts 126 and breaks the continuity of the holding circuit of relay 73. This deenergizes the relay and opens the contacts 114 which in turn deenergizes carriage magnet 115. The carriage return spring 127 thereupon returns the carriage to the right against stop 128.

As the selector bars 107, 110 and 111 moved to the left in the initial motion of the carriage they engaged return lever 129 and turned it around its center point against the tension of its spring 130. Latch 131 immediately snapped into position and held the return lever so that the selector bars were not returned to the right at that time.

As the return lever 129 snapped into the notch of latch 131 printing contacts 132 closed and printing relay 133 was energized. This closed contacts 134 and energized printing solenoid 135. This solenoid pulls the armature 136 downwards with its extension 137 which is pivoted to printing bail 124, the bail being pivoted at an intermediate point 138. This moves the bail upwards (Fig. 7) and permits the pull bar 123 to drop into the aligned notches 122 in the selector bars. As it does this the upwardly moving projection 139 engages the hump 125 in the pull bar and moves it upwards with the bail. This throws the type bar 141 downwards and 50 strikes the type-pallet against the ribbon on platen 142. This prints the letter H.

Just at the time that the armature 136 of the printing solenoid completed its movement projection 143 engaged the latch 131 and permitted the return lever 129 to return the three selector bars to the right whereupon leaf spring 120 snapped into groove 144 which holds these three bars together with the others in their initial position. At about this time projection 145 opens switch contacts 146 and deenergizes the printing relay and the printing solenoid magnet. The plunger is then returned to its initial position by spring 147 (Fig. 7). This returns the pull bar and brings the printing bail 124 against 65 the hump 125 of the pull bar and moves it outward clear of the selector bars.

The selected letter H has thus been printed and all mechanism of the printer has returned to the original position. However, the selection of the next transmitted letter was not held up pending the operating of the printing mechanism. Since the relay sr2 was reset when segment s'r3 was engaged by brush 44r and relays sr5 and sr6 were reset when segment s'r1 was similarly en-

gaged, those relays were available for the subsequent signal unit. The selector magnets assumed their inoperated position before the printer magnet was energized so signals can be stored in the printer as soon as the brush 24r reaches the corresponding commutator segments. In view of this the printing mechanism has substantially one full revolution of the commutator for completion of the printing operation itself. During this printing operation the signal code reception continues without interruption as the impulses, in effect, are stored while the printing is completed.

The letters AND will be printed similarly to the letter H and the operation need not be further described.

Since the printing system of my invention operates independently of the tape transmitters and printers of other channels its greatest advantage over prior art systems is in single channel printing operations.

The transmission system of Fig. 1 can be used with the receiver of my above mentioned application and the receiver of this application can 25 also be used with the transmitter of such application. Also other receivers could be designed for working with the transmitter of this case and other transmitters could be designed for working with the receiver disclosed herein. Therefore, the transmitters and receivers are not limited to any one cooperating system.

The invention has been disclosed in connection with a seven-unit code group, but it is not limited thereto. It may be used with other code groups of a different number of units; for example, the five-unit code group.

I have illustrated circuit arrangements that have been found satisfactory but the invention is not to be limited thereto as various changes could be made without departing from the spirit of the invention.

Having described my invention, what I claim is:

1. In a transmitter for multiunit code characters, a tape transmitter for sending the signal units to indicate a message, an outgoing line, a switch for each code unit, means for connecting the switches in succession to said line, a magnet for each code unit each having an armature for positioning one of said switches in a signal position, means for energizing the magnets for a new character in the middle of the transmission of the previous character and means for locking the armatures of the magnets for the untransmitted units of said previous character until their associated switches have been connected to the outgoing line.

2. In a transmitter for multiunit code characters, a tape transmitter for sending the signal units to indicate a message, an outgoing line, a switch for each code unit, means for connecting the switches in succession to said line, a magnet for each code unit each having an armature for positioning one of said switches in a signal position, the coils of said magnets being connected to the tape transmitter, means for moving the tape for energization of the magnets for a new character before the signal units have been transmitted for the previous tape setting and means for locking the armatures of the magnets for the remaining units until their associated switches have been connected to the outgoing line.

3. In a transmitter for multiunit code char-

acters, an outgoing line, a switch for each code unit, means for connecting the switches in succession to said line, a magnet for each code unit each having an armature for positioning one of said switches in one signal position, means for energizing the magnets in accordance with the characters to be transmitted, a restoring magnet having an armature for moving the switches from said position to another signal position after the time for a predetermined number of signal units for each code group has passed, and a second restoring magnet having an armature for moving the remaining switches from said position to the other position after the time for all the signal units of such code group has passed.

4. In a transmitter for multiunit code characters, a tape transmitter for sending the signal units to indicate a message, an outgoing line, a switch for each code unit, means for connecting the switches in succession to said line, a magnet for each code unit each having an armature for moving one of said switches to one signal position, the coils of said magnets being connected to the tape transmitter for energization thereby, a restoring magnet having an armature for moving the switches from said position to another signal position after the time for a predetermined number of signal units for each code group has passed, and a second restoring magnet having an armature for moving the remaining switches from said position to the other position after the time for all the signal units of such code group has passed.

5. In a receiving system for multiunit code characters, a conductor for receiving the incoming signal units, a printer having a selector magnet for each code unit, a selector switch in the circuit of the coil of each selector magnet, a relay for each signal unit each having an armature for operating one of said selector switches as its signal unit is received over said conductor, a restoring magnet having an armature for moving operated selector switches to unoperated position after the time for a predetermined number of signal units for a code group has passed and a second restoring magnet having an armature for moving the remaining operated selector switches to their unoperated position before the signal units of the next code group have been received.

6. In a receiving system for multiunit equal length code characters, a conductor for receiving the incoming signal units, a printer having a selector magnet for each code unit, a selector switch in the circuit of the coil of each selector magnet, a relay for each signal unit each having an armature for operating one of said selector switches as its signal unit is received over said conductor, a restoring magnet having an armature for moving operated selector switches to unoperated position after the time for a predetermined number of signal units for a code group has passed and a second restoring magnet having an armature for moving the remaining operated selector switches to unoperated position after the time for all the signal units of such code group has passed.

7. In a receiving system for multiunit equal length code characters, a conductor for receiving the incoming signal units, a printer having a selector magnet for each code unit, a selector switch in the circuit of the coil of each selector magnet, a relay for each signal unit each having an armature operating one of said selector switches as its signal unit is received over said conductor, a restoring magnet having an arm-

ture for moving operated selector switches to unoperated position, a restoring relay for energizing the restoring magnet after the time for a predetermined number of signal units for a code group has passed, a second restoring magnet having an armature for moving the remaining operated selector switches to unoperated position and a second restoring relay for energizing the second restoring magnet after the time for all the signal units of such code group has passed.

8. In a receiving system for multiunit equal length code characters, a conductor for receiving the incoming signal units, a printer having a selector magnet for each code unit, a selector switch in the circuit of the coil of each selector magnet, a relay for each signal unit each having an armature operating a selector switch to closed position as its signal unit is received over said conductor, a restoring magnet having an armature for moving operated selector switches to unoperated position, a restoring relay for energizing the restoring magnet after the time for a predetermined number of signal units for a code group has passed, a second restoring magnet having an armature for moving the remaining operated selector switches to unoperated position and a second restoring relay for energizing the second restoring magnet after the time for all the signal units of such code group has passed, each of said restoring magnets having means for restoring its energizing relay.

9. In an electric telegraph system for multi-unit equal-length code characters, two groups of relays, a movable switch lever for each relay, means controlled by the armatures of said relays for positioning the switch levers in one position, means for simultaneously energizing a predetermined number of said relays for each code character of a message, means whereby the armatures of the energized relays of one group cause the first means to position the switch levers in another position, means connected with the first means for locking the armatures of the other group of relays from movement and means for moving the switch levers of the second group of relays from the second-mentioned position to the first-mentioned position and for causing the third means to release the armatures.

10. In an electric telegraph system for multi-unit equal-length code characters, two groups of relays, a movable switch lever for each relay biased to engage a contact of one potential, means controlled by the armatures of said relays for positioning the switch levers to engage a contact of another potential and for releasing them for engagement with the contact of the first potential, means for simultaneously energizing a predetermined number of said relays for each code character of a message, means whereby each energized relay of one group immediately moves its armature and the switch lever moves into engagement with the contact of the first potential, means connected with the first means for locking the armatures of the other group from movement and means for moving the switch levers of the second group from engagement with the contact of the first potential to engage the contact of the second potential and for moving the locking means to release the armatures.

11. In an electric telegraph system for multi-unit equal-length code characters, two groups of relays, a movable switch lever for each relay biased to a first position, arms engaging the armatures of the relays for supporting the switch levers in a second position and for releasing them

for movement to the first position, means for simultaneously energizing a predetermined number of said relays for each code character of a message, means whereby each energized relay of one group immediately moves its armature from engagement with the first means and its switch lever moves to said first position, lugs on the arms associated with the armatures of the other group for locking their associated armatures from movement and means for moving the switch levers of the second group from said first position to the second position and substantially simultaneously moving the arms of said second group to unlock their engaging armatures.

12. In an electric telegraph system for multi-unit equal-length code characters, two groups of relays, a movable switch lever for each relay biased to a first position, means engaging the armatures of the relays for supporting the switch levers in a second position and for releasing them for movement to the first position, means for simultaneously energizing a predetermined number of said relays for each code character of a message, means whereby each energized relay of one group immediately moves its armature from engagement with the first-mentioned means and its switch lever moves to said first position, means connected with the first-mentioned means for locking the armatures of the other group from movement, means for moving the switch levers of the first group from said first position to the second position, and means for moving the switch levers of the second group from said first position to the second position and substantially simultaneously moving said locking means to release their engaging armatures.

13. In an electric telegraph system for multi-unit equal-length code characters, an outgoing channel, a first and second group of relays, a movable switch lever for each relay biased to a first position, means engaging the armatures of the relays for supporting the switch levers in a second position and for releasing them for movement to the first position, means for electrically connecting the switch levers in succession to said channel, means operated after the connection of the last switch lever of the first group to said channel for simultaneously energizing a predetermined number of said relays for each code character of a message, means whereby each energized relay of the first group immediately moves its armature from engagement with the first means and its switch lever moves to said first position, locking means connected with the first means for holding the armatures of the second group from movement and means for moving the switch levers of the second group of relays from said first position to the second position and substantially simultaneously moving said locking means to release the armatures.

14. In an electric telegraph system for multi-unit equal-length code characters, an outgoing channel, a first and a second group of relays, a movable switch lever for each relay biased to mark position, means engaging the armatures of the relays for supporting the switch levers in space position and for releasing them for movement to mark position, means for electrically connecting the switch levers in succession to said channel, means operated after the connection of the last switch lever of the first group of relays to said channel for simultaneously energizing a predetermined number of said relays for each code character of a message, means whereby each energized relay of the first group immedi-

ately moves its armature from engagement with the first means and its switch lever moves to mark position, means connected with the first means for locking the armatures of the relays of the second group from movement means for moving the switch levers of the second group of relays from mark position to space position and for moving the locking means to release the armatures, and means for causing the last-mentioned means to operate after the connection of the last switch lever of the first group to said channel.

15. In an electric telegraph system for multi-unit equal-length code characters, an incoming channel, two groups of relays, a movable switch lever for each relay, means controlled by the armatures of said relays for positioning the switch levers in one position, means for electrically connecting the coils of said relays in succession to said channel, means whereby the armatures of the energized relays of one group causes the first means to position the levers in the first position, means connected with the first means for locking the armatures of the other group of relays from movement, a printer having selector bars, an operating magnet, a printer selector magnet electrically connected to each of said switch levers and having means when energized to connect a selector bar to the operating magnet for movement thereby, means for moving the switch levers of the second group of relays from the second position to the first position and for moving said locking means to release the armatures and means for energizing said operating magnet after connection of the last relay of the second group to said channel.

16. In an electric telegraph system for multi-unit equal-length code characters, an incoming channel, relays arranged in a first and a second group, a movable switch lever for each relay biased to a first position, means controlled by the armatures of said relays for positioning the switch levers in a second position, means for electrically connecting the coils of said relays in succession to said channel, means whereby the armatures of the energized relays of the first group move and the first means positions the levers in a second position, means connected with the first means for locking the armatures of the second group of relays from movement, a printer having selector bars, an operating magnet, a printer selector magnet electrically connected to each of said switch levers and having means when energized to connect a selector bar to the operating magnet for movement thereby, means for moving the switch levers of the second group of relays from the first position to the second position and for moving said locking means to release the armatures after the connection of the coil of the last relay of the second group to said channel and means for energizing said operating magnet after said connection of the last relay of the second group to said channel.

17. In an electric telegraph system for multi-unit equal-length code characters, an incoming channel, relays arranged in a first and a second group, a movable switch lever for each relay biased to mark position, means engaging the armatures of the relays for supporting the switch levers in space position and for releasing them for movement to mark position, means for electrically connecting the coils of said relays in succession to said channel, means whereby each energized relay of the first group immediately moves its armature from engagement with the first means and its lever moves to mark position,

means operated after the connection of the coil of the third relay of the second group to said channel for moving any unsupported switch lever of the first group from mark position to space position, means connected with the first means for locking the armatures of the second group of relays from movement, a printer having selector bars, an operating magnet, a printer selector magnet electrically connected to each of said switch levers and having means when energized to connect a selector bar to the operating magnet for movement thereby and means for moving the switch levers of the second group of relays from mark position to space position and substantially simultaneously moving the locking means to release the armatures after the connection of the coil of the last relay of the second group to said channel, and means for energizing said operating magnet after said connection has been made.

18. In a receiving system for multi-unit code characters, a conductor for receiving the incoming signal units, a printer having a selector magnet for each code unit, a selector switch in the circuit of the coil of each selector magnet, a relay for each signal unit, means whereby the armature of each relay moves one of said selector

switches to one position as its signal unit is received over said conductor, means for moving the operated selector switches to unoperated position after the time for a predetermined number of signal units for a code group has passed and means for moving the remaining operated selector switches to their unoperated position before the signal units of the next character have been received.

19. In a receiving system for multi-unit equal-length code characters, a conductor for receiving the incoming signal units, a printer having a selector magnet for each code unit, a selector switch in the circuit of the coil of each selector magnet, a relay for each signal unit, means whereby the armature of each relay moves one of said selector switches to closed position as its signal unit is received over said conductor, means for moving closed selector switches to open position after the time for the reception of a predetermined number of signal units for a code group has passed and means for moving the remaining closed selector switches to open position after the time for the reception of all the signal units of such code group has passed.

JAMES A. SPENCER.
